Primary Examiner — Rashida C. Walshon(74) *Attorney, Agent, or Firm* — Joseph G Swan, PC(57) **CLAIM**

The ornamental design for a shoe upper, as shown and described.

DESCRIPTION

FIG. 1 is a side elevational view of a shoe upper according to the present invention; and,

FIG. 2 is a perspective view of the shoe upper.

The broken lines in the drawings represent context that forms no part of the claimed design.

1 Claim, 2 Drawing Sheets(56)
